UNITED STATES PATENT OFFICE.

WILLIAM H. WOOD, OF CLEVELAND, OHIO.

SEPARATOR FOR STORAGE BATTERIES.

No Drawing.

Application filed April 17, 1920. Serial No. 374,711.

To all whom it may concern:

Be it known that I, WILLIAM H. WOOD, a citizen of the United States, residing at Cleveland, in the county of Cuyahoga and State of Ohio, have invented a certain new and useful Improvement in Separators for Storage Batteries, of which the following is a full, clear, and exact description.

This invention relates to separators for storage batteries and has for its object the provision of a porous separator which shall be insoluble in the electrolyte. The source of material which I employ is the hair of fleece of mammalian animals, for example that of beef creatures, inasmuch as great quantities of this material is thrown away every year, although that of any other hairy animal can equally well be employed. After descaling this material is either knitted, netted, felted or otherwise built up, and may also be embedded in or surrounded by rubber or other substances; all of such material is alike in this, that in the natural state each strand is armored with a complete coating of minute slippery scales which resist wetting, diminish friction, and prevent adhesion of the same either to other hairs or to other objects and it is largely by these qualities that such material is distinguished from vegetable fibers, and it is also to this cause that fabrics woven of hair possess their peculiar unpleasant qualities and that ropes or threads of hair have little strength, despite the very great strength of the individual hairs. According to my invention the exterior scaly portion of the hair is first removed by soaking in a suitable chemical, such as sodium sulphite solution or milk of lime. I then spin the resulting material into thread or cord, producing thereby an article of great strength which is also capable of a great deal of flexure without breaking, and which also possesses the advantage of insolubility in all acids except the very strongest.

The raw material which I preferably employ is slaughter-house hair or tanner's hair, although I may also employ hair from any source. After treating the same with sodium sulphite, milk of lime, or other substance, and after having thoroughly cleansed the same and removed the spent solution, I employ the same either in the felted, woven,

knitted, or netted state for locations in which an acid resistant fabric is required such as the clothing of those engaged in chemical industries and in the construction of separators for storage batteries and for the filtration of acid liquids. Such a fibrous material becomes easily embedded in the rubber as is necessary in the manufacture of tires, battery separators; and owing to its very great tensile strength and its high resistance to acid action, it possesses many qualities of great value not present in any other material while having the further advantage of extreme cheapness owing to its derivation from what is now a waste product.

Having thus described my invention, what I claim is:

1. A fabric made of rubber composition traversed by strands of mammalian hair from which the scaly exterior portions have been removed.

2. A rubber-impregnated, reinforced article in which the reinforcing material consists essentially of mammalian hair from which the scaly exterior portions have been removed.

3. A separator for storage batteries consisting essentially of a plate of material insoluble in the electrolyte and having therein reinforcing and pore-forming fibers consisting of mammalian hair from which the exterior scaly portions have been chemically removed.

4. A separator for storage batteries consisting of a sheet of fabric made from mammalian hair whose scaly exterior portions have been chemically removed, said fabric impregnated with rubber composition.

5. A separator for storage batteries consisting essentially of a felted sheet of mammalian hair from which the external scaly portions have been removed, said sheet being impregnated with sufficient rubber material to afford mechanical strength without overcoming porosity.

6. A separator for storage batteries containing mammalian hair whose scaly exterior portions have been removed.

In testimony whereof, I hereunto affix my signature.

WILLIAM H. WOOD.
